UNITED STATES PATENT OFFICE.

WILLIAM W. HOBE, OF NEW YORK, N. Y., ASSIGNOR TO HOBE BUTTON COMPANY, INC.,
A CORPORATION OF NEW YORK.

DESIGN FOR A BUTTON.

52,531.

Specification for Design.

Patented Oct. 8, 1918.

Application filed June 7, 1918. Serial No. 238,782. Term of patent 3½ years.

To all whom it may concern:

Be it known that I, WILLIAM W. HOBE, a subject of the Emperor of Germany, residing at New York, county of New York, and State of New York, have invented a new, original, and ornamental Design for Buttons, of which the following is a specification, reference being had to the accompanying drawing, forming part thereof, in which—

Figure 1 is a plan view of my newly designed button and Fig. 2 is an end view thereof.

My newly designed button is perfectly circular, but is beveled on the front face thereof to form a crescent. The button comprises three layers, a top layer A and a bot-

tom layer B of the same color and included therebetween is a layer C of color contrasting with the top and bottom layers. These three layers are beveled respectively as at D, E and F to provide a crescent as shown. It will be noted that intermediate layer C is of larger width than the top and bottom layers and when beveled the crescent F stands out prominently in color contrast and by reason of its greater width.

I claim,

The ornamental design for a button as shown and described.

WILLIAM W. HOBE.

Witness:

B. M. SWIFT.
